UNITED STATES PATENT OFFICE.

WILLIAM H. HOSCHKE, OF BROOKLYN, ASSIGNOR TO M. J. PAILLARD & CO.,
OF NEW YORK, N. Y.

DESIGN FOR A CIGAR-LIGHTER.

SPECIFICATION forming part of Design No. 21,235, dated December 15, 1891.

Application filed November 9, 1891. Serial No. 411,405. Term of patent 7 years.

To all whom it may concern:

Be it known that I, WILLIAM H. HOSCHKE, a citizen of the United States, and a resident of Brooklyn, in the county of Kings and State 5 of New York, have invented a certain new Design for a Cigar-Lighter, of which the following is a specification.

The accompanying drawing shows a perspective view of my new design for a cigar-lighting stand.

The leading feature of the design for the cigar-lighting stand consists of an easel, a lamp-body on the top of the easel, and a wheel supported on the front of the easel.

15 A is the easel; B, the wheel; C, the lamp, and E are cylindrical receptacles at the sides of the wheel.

Having thus described my invention, what I claim as new, and desire to secure by Letters Patent, is—

A design for a cigar-lighting stand, substantially as shown herein and described, the same comprising an easel, a wheel on the front of the easel, and a lamp on the top of the easel, substantially as set forth.

In testimony that I claim the foregoing as my invention I have signed my name in presence of two subscribing witnesses.

WILLIAM H. HOSCHKE.

Witnesses:

ALBERT LANCELOT,
R. H. SCHLEY.
